[57] **CLAIM**

The ornamental design for a packaging tray or the like, as shown and described.

DESCRIPTION

FIG. 1 is a top perspective view of a packaging tray or the like showing my new design;

FIG. 2 is an end elevational view thereof, the opposite end being substantially a mirror image of that shown;

FIG. 3 is a side elevational view thereof, the opposite side being substantially a mirror image of that shown; and

FIG. 4 is a bottom plan view thereof.

FIG. 1

FIG. 2

FIG. 3

FIG. 4
